UNITED STATES PATENT OFFICE.

ARCHIBALD MONTGOMERY LOW, OF BROOK GREEN, LONDON, ENGLAND.

ELECTRIC IGNITION APPLIANCE.

971,908.

Specification of Letters Patent. Patented Oct. 4, 1910

Application filed August 30, 1909. Serial No. 515,213.

To all whom it may concern:

Be it known that I, ARCHIBALD MONTGOMERY LOW, a subject of the King of England, residing at Brook Green, London, W., in England, have invented certain new and useful Improvements in and Relating to Electric Ignition Appliances, of which the following is a specification.

This invention relates to electric ignition appliances, principally for igniting the charge in internal combustion engines, and consists in novel arrangements and constructions of the surfaces at which the spark occurs with the object of providing a more suitable spark.

It has been previously proposed to use igniting devices in which one of the electrodes is in the form of a cup partially or entirely inclosing the other electrode which is of pointed formation, but in this known arrangement the cup electrode is in the form of a plate of thin sheet metal so that it remains hot whereby the oil admitted to the combustion chamber becomes instantly vaporized to more effectively ignite and the flame tends as it spreads to the mixture in the cylinder to have a scouring effect on the terminals and keep the parts clean. In this form also the spark produced between the electrodes is always formed at or about the center of the plate electrode.

In the present invention the cup electrode is of a size commensurate with the spark gap, that is to say, taken in conjunction with the co-acting electrode, the spark between said electrodes can extend to any point of the surface of the cup whereby the cup and co-acting electrode have such a relation that a spark of an extremely detonative character is produced which by its own rapidity and violence not only keeps the electrodes clean but ignites the gases more quickly and with greater certainty and efficiency even when the charge is very weak.

45 The electrodes may be in any number or in any number of pairs and may be arranged to suit respectively different ignitions, such as coil and accumulator or magneto.

The actual construction of the plug is of minor importance and may be effected in any appropriate or convenient manner.

An embodiment of the invention is shown in the annexed drawing which shows sufficient of the base of a sparking plug for comprehension of the invention, Figure 1 being

a partial plan view from below and Fig. 2 a vertical central section.

In said drawings *a* designates the usual hollow base of the plug screw threaded for engaging a tapped hole in the cylinder-cover of the engine, and *b* the central electrode which in the construction illustrated is provided at its protruding lower end with two diametrically opposite hemispherical concavities or cups *c* into which extend the pointed ends *d* of the other electrodes *e* connected in any convenient manner to the conductive base *a*. The distance of the points *d* of the electrodes *e* from the bases of the cups depends largely upon the conditions of working and nature of electric source used but for the majority of cases it is preferred that said points penetrate the cups to an extent that their extremities extend to and are definitely located at the axial centers of the cups or slightly beyond same interiorly of the concavity as shown in the drawings.

The improvements in electrode construction described above may of course be fitted to any suitable plugs.

The invention can be applied to any kind of sparking surfaces of the nature described irrespective of their uses or applications.

What I claim as my invention and desire to secure by Letters Patent of the United States is:

1. An electric ignition appliance comprising a pair of electrodes disposed with a spark gap therebetween, one of said electrodes having a hemispherical concavity of a size commensurate with the spark gap and the other electrode having a point entering said concavity and terminating at substantially the axial center thereof so that the spark may reach any part of the wall of the concavity with a uniform jump.

2. An electric ignition appliance comprising an electrode having a plurality of hemispherical concavities each commensurate with the desired spark gap, and a plurality of pointed electrodes one for each concavity, and terminating at substantially the axial center thereof so that the spark may reach any part of the wall of the concavity with a uniform jump.

3. An electric ignition appliance comprising a plurality of pairs of electrodes, each pair being disposed with a spark gap therebetween, one electrode of each pair having a hemispherical concavity of a size com-

mensurate with the desired spark gap, and the other electrode of each pair having a point entered into the hemispherical concavity of the related electrode to a point adjacent the axial center thereof so that the spark will be uniform between the point and any part of the wall of the concavity.

In witness whereof I have signed this specification in the presence of two witnesses.

ARCHIBALD MONTGOMERY LOW.
